VEHICLE FLOORBOARD COVER OR THE LIKE

Hyman D. Bowman, 801 W. Morgan St.,
Raleigh, N.C. 27603

Filed Dec. 29, 1969, Ser. No. 20,679

Term of patent 14 years

Int. Cl. D12—16

U.S. Cl. D14—5

FIG. 1 is a top perspective of a vehicle floorboard cover or the like, showing my new design;

FIG. 2 is a section taken through lines 2—2 of FIG. 1.

I claim:

The ornamental design for a vehicle floorboard cover or the like, as shown.
